UNITED STATES PATENT OFFICE

2,477,629

STABILIZING AND GUIDE APPARATUS FOR
LIFTER ROOF TANKS

Donald E. Larson, Eureka, Calif., assignor to Chicago Bridge & Iron Company, a corporation of Illinois

Application July 13, 1946, Serial No. 683,333

4 Claims. (Cl. 48—176)

1

This invention relates to a lifter roof tank, and particularly to a stabilizing and guide apparatus for said tank.

Lifter roof tanks are used for the storage of gas and mixtures of liquid and gas. As the pressure within the tank is increased and decreased the roof rises and falls. The lifter roof is located over the shell of the tank, which constitutes the main storage portion, and flexible sealing means are provided between the shell and the roof. This sealing means is ordinarily fabric impregnated with a flexible impervious solid such as synthetic rubber. It has been found necessary in tanks of this type that stabilizing means be provided for maintaining the roof substantially level at all times, even when subjected to unequal loads. It is also advisable to provide guide means for preventing rotation of the roof with its subsequent twisting of the flexible sealing member. The usual relief valves and safety devices are also employed.

In the present invention improved stabilizing and guide means have been provided for maintaining the roof level at all times and for preventing rotation of the roof. These stabilizing and guide means may be used not only on a dry seal roof wherein the sealing member is the previously described flexible sealing member, but may also be used on wet seal roofs wherein a liquid is used to seal the area between the roof and the shell. The invention broadly comprises a plurality of substantially parallel depending arms rotatably attached at their upper ends to the roof with each arm rotatably attached at its lower end to a movable member located adjacent the shell of the tank, a guide member on the tank shell for guiding each of said movable members in a helical path against the shell as the roof rises and falls, and guide means between the roof and the shell for preventing rotation of the roof as it rises and falls. The guide members are all arranged at substantially the same acute angle with respect to the horizontal and all extend in the same direction around the shell.

The invention will be described as related to the embodiments shown in the accompanying drawings. Of the drawings Fig. 1 is a fragmentary plan view of a lifter roof tank embodying the invention with portions broken away for clarity of illustration; Fig. 2 is an elevation of said tank showing the roof in its highest position; Fig. 3 is a vertical section taken along line 3—3 of Fig. 2; Fig. 4 is a fragmentary elevation showing the roof in its lowest position; Fig. 5 is an elevation of an alternate embodiment of the invention showing

2

the roof in its highest position; and Fig. 6 is an elevation of said alternate embodiment showing the roof in its lowest position.

The lifter roof tank comprises a shell 10, a lifter roof 11 thereover, a depending skirt 12 on the edge of the roof, and beyond the shell 10, and a flexible sealing member 13 extending between the skirt 12 and the top of the shell 10.

Located around the tank and rotatably attached to the bottom of the skirt 12 are a plurality of equally spaced depending arms 14. Each arm 14 has its top attached to a downwardly extending mounting 15 on the inner end of a horizontal bracket 16 located at the bottom of the skirt 12. The bottom end of each arm 14 is rotatably attached to a horizontal bar 17 extending inwardly toward the shell. Around the shell, but spaced therefrom, there is located a structural member 18 formed of pipe and having the shape of a regular polygon. Each horizontal bar 17 is attached to the structural member 18 at an apex of the polygon.

On the inner end of each bracket 16 there is located a roller 19 held flat against the shell 10. On either side of each roller 19 there is located a guide member 20 formed of angle iron attached to the shell along one flange, with the other flanges of two of the guide members extending toward each other. These guide members 20 are vertically arranged and serve to prevent rotation of the roof as it rises and falls.

At the inner end of each horizontal bar 17 is located a second roller 21 also held flat against the shell 10. Each roller is provided with two similar guide members 22 also formed of pieces of angle iron attached to the shell 10. Each pair of guide members 22 are arranged at substantially 45° angles with respect to the horizontal and are shaped like a section of a helix. All of these latter guide members have the same angle and extend in the same direction around the shell.

The horizontal structural member 18 is formed of straight lengths of pipe coupled together by coupling members 23 forming the apices of the polygon. Each horizontal bar 17 is attached to a coupling member 23. The structural member is reinforced at each apex by a cross bar 24 formed of a piece of angle iron. At its midpoint each cross bar 24 is adjacent the shell, and the bottom end of a depending arm 14 extends through this midpoint. The bottom end 25 of each depending arm 14 is flattened, with the flattened portion being provided with a hole through which the horizontal bar extends. The top end 26 of each depending arm 14 is also flattened, and is

provided with a hole through which a short rod 27 extends. This short rod 27 is held by a mounting 15.

In the embodiment shown in Figs. 1 to 4 inclusive the tops of the lower guide members 22 are substantially joined to the bottoms of the vertical guide members 20. There is provided a short bar 28 across the bottom of each pair of vertical guide members 20 to limit the upward movement of the roof 11. In the embodiment shown in Figs. 5 and 6 each pair of sloped bottom guide members 22a is offset from the vertical guide members 20 with the bottom guide members 22a being beneath the vertical guide members 20.

As the roof rises and falls the vertical guide members 20 serve to prevent rotation of the roof. The sloped guide members 22 and 22a combined with the horizontal polygonal structural member 18 serve to maintain the roof substantially horizontal at all times, and equalize the load on the 15 roof.

Having described my invention as related to the embodiments shown in the accompanying drawings, it is my intention that the invention be not limited by any of the details of description unless otherwise specified, but rather be construed broadly within its spirit and scope as set out in the accompanying claims.

I claim:

1. In a lifter roof tank comprising a shell and a movable roof thereover having a downwardly extending skirt attached thereto and located beyond the shell, stabilizing and guide means comprising inclined roller guides attached below corresponding vertical roller guides, both roller guides being attached to the outside of the shell, a plurality of rollers attached to the roof skirt and engaging the vertical guides, a plurality of rollers

engaging the inclined guides and attached to the apices of a common horizontal structural member of polygonal shape extending around the shell but spaced therefrom, and arms of equal length connected at one end to the roller attached to the roof skirt and connected at the other end to the rollers engaging the inclined guides at the apices of said polygonal member, each of said arms being movable in a plane substantially parallel to the shell wall.

10 2. The stabilizing and guide means of claim 1 wherein the top of each inclined guide is substantially aligned with the bottom of its corresponding vertical guide.

15 3. The stabilizing and guide means of claim 1 wherein the top of each inclined guide is offset to one side of and above the bottom of its corresponding vertical guide.

20 4. In a lifter roof tank comprising a shell and a movable roof thereover having a downwardly extending skirt attached thereto and located beyond the shell, stabilizing and guide means comprising a plurality of inclined roller guides attached to the outside of the shell, a plurality of vertical roller guides attached to the outside of the shell, a plurality of rollers attached to the roof skirt and engaging the vertical guides, a plurality of rollers engaging the inclined guides and attached to a common horizontal structural member of annular shape extending around the shell but spaced therefrom, and arms of equal length connected at one end to the roof skirt and connected at the other end to the structural member, each of said arms being movable in a plane substantially parallel to the shell wall.

25 DONALD E. LARSON.
